UNITED STATES PATENT OFFICE.

JAMES LEWALLEN, OF ONEIDA, TENNESSEE.

BEARD-SOFTENING PREPARATION.

No Drawing.

Application filed July 29, 1925. Serial No. 46,885.

The object of this invention is to provide a preparation for use in shaving and by means of which the beard may be effectively softened and dirt and grease removed from the pores of the skin.

A further aim of the invention is to provide a preparation of the character described which may be safely employed either by the barber trade or by those who shave themselves and which may be placed upon the market at a low cost.

Other objects and advantages will be apparent during the course of the following description.

15 The improved composition consists of the following ingredients:

Boiling rain or distilled water 10½ ounces, bicarbonate of soda 5 teaspoonsful, grain alcohol 4½ ounces, olive oil 1 ounce.

20 In compounding the improved preparation, the bicarbonate of soda is first added to the rain water and this is shaken well until the bicarbonate of soda is thoroughly dissolved. To this is added the grain alcohol 25 and then the olive oil is added and all of the ingredients thoroughly mixed together.

The soda will remove all dirt and grease from the pores of the skin and will effectively and quickly soften the beard, while 30 the alcohol will flavor the preparation and at the same time act as an antiseptic. The olive oil has been found to possess a marked soothing effect and at the same time softens the skin and the beard.

35 The improved preparation when applied correctly will make the beard soft and easy to shave and leave the skin soft, velvety and cool. No chapping or irritation of the skin

results from the use of this preparation.

The preparation is preferably applied by 40 moistening the face thoroughly with the preparation and rubbing it thoroughly into the pores of the skin. A soapy lather is now applied in the usual way. After this

the face is massaged for about two minutes 45 and the face is then washed with a wet towel. Now the lather is spread and the beard may be shaved.

The barber may shave a person in a comparatively short time and easier than in accordance with the old methods now generally followed. No discomfort to the person being shaved will be experienced and at

this point it is pointed out that the use of the improved preparation will relieve the person being shaved of that discomfort sometimes 50 present during shaving. Also the razors will not require frequent honing and stropping when this preparation is employed.

With reference to the foregoing description 55 it will be seen that the improved preparation provides a simple and economical lotion for use in shaving and which is employed in connection with the lather or it may even be employed by itself for the purpose of softening the beard.

Having thus described the invention, what is claimed is:

A preparation for use in cleansing and softening beards preparatory to shaving and consisting of a mixture of 10½ ounces 70 of boiled water, 5 teaspoonsful of bicarbonate of soda, 4½ ounces of grain alcohol, and 1 ounce of olive oil.

In testimony whereof I affix my signature.

JAMES LEWALLEN.
